UNITED STATES PATENT OFFICE.

HENRY ROBERTS, OF PASADENA, CALIFORNIA.

GRAPNEL.

No. 839,036.

Specification of Letters Patent.

Patented Dec. 18, 1906.

Application filed December 26, 1905. Serial No. 293,217.

To all whom it may concern:

Be it known that I, HENRY ROBERTS, a citizen of the United States, residing at Pasadena, in the county of Los Angeles and State of California, have invented a new and useful Grapnel, of which the following is a specification.

It is of the objects of this invention to provide a load-holding device adapted to be readily attached to and detached from hay and like coarse bulky material, whether baled or loose; to provide a tripping device which may be readily operated to trip the load-holding hook at a distance therefrom by means of a rope or other connection, and to provide a hook with lever-operated means whereby said hook may be readily operated to drop its load by a slight pull on a trip-rope.

This invention relates to a hoisting and releasing device adapted to be employed in connection with the hoist and carrier described in another application for patent filed by me in the United States Patent Office contemporaneously herewith, Serial No. 293,218.

Other objects and advantages may appear from the following detailed description, taken in connection with the accompanying drawings, illustrative of the invention, in which—

Figure 1 is a side elevation of the device in load-holding position, one side of the frame being broken away to show interior parts. Fig. 2 is a view similar to Fig. 1, showing parts in position assumed when the hook is to drop its load. Fig. 3 is a front elevation of the device with parts in same position as in Fig. 1.

The grapnel comprises a frame, a hook pivoted thereto, and a toggle connected to lock and to operate the hook.

The frame 1 may be formed of a single piece of metal bent into a shape approximating that of an inverted U, being provided with side pieces 2 and 3 and a uniting-piece 4 at the top, which may be perforated at 4' to receive a swivel 5, having an eye 5'.

6 7 8 designate pivot bolts or pins for spacing apart the side pieces 2 and 3 and pivotally supporting parts hereinafter described.

9 designates the load-carrying hook, which is provided at its upper end with a segmental gear 10, the teeth 11 of which engage teeth 12 of another segmental gear 13, having an extension 14, to each side of which is pivoted at 15 a double link 16, which is in turn pivoted at 17 to the short end of a lever 18, having

its fulcrum at bolt 6, on which it is pivoted to oppositely-disposed adjacent extensions 19 of the frame 1.

Hook 9 is preferably provided at each side 60 with a perforated boss 9' for receiving bolt 8 and spacing side pieces 2 and 3 a short distance away from gear 10. Gear 13 and lever 18 may likewise be respectively provided with bosses 13' and 18'.

In Fig. 1 the parts are shown in holding position, the hook 9 being swung forward into position for carrying a load, an extension 20 at the upper end of the hook abutting against extension 14 of gear 13, the pivots 6, 17, and 15 of lever 18 and link 16 being nearly in alinement, the pivot 17 being adapted to stand a little back of the line toward pivot 7 to lock the hook against swinging rearwardly into the releasing position. (Shown in Fig. 2.) Lever 18 may be provided at the upper end with an eye 21, to which is attached the trip-rope 22 for operating said lever to throw the hook rearwardly into the releasing position. The hook may be readily 75 grasped by the hand and canted forward from this position for attachment to a new load. A rope or other connection 52 may be attached to eye 5' of swivel 5 for suspending the device from the hoist and carrier described in my aforementioned application for patent or from any other appropriate device.

From the foregoing description it will be readily understood that in practical operation a pull on trip-rope 22 will operate lever 18, initial gear 13 through link 16, and final gear 10, thereby swinging the point of hook 9 backwardly and releasing the load, which may thus be dropped from the hook when in an elevated position. 25 designates cotters for holding the bolts in place.

It is to be noted that the pivoted lever 18, link 16, and gear 13 form a toggle connected with the hook through its gear-teeth 11 to 100 operate and to lock the hook 9.

Link 16 rests against bosses 13' when in the locking position.

The side bars 2 and 3, which compose the double frame of the hook, form a housing for the toggle-actuated gears 10 and 13. The actuated arm 18 of the toggle is pivoted to the frame forwardly of the pivot of the hook in such a way that said actuating-arm 18 will extend adjacent to and substantially 110 parallel with the frame, locking the hook in its forward or holding position. This con-

struction provides a strong and compact operating device for moving the hook 9 and for locking it in its holding position.

What I claim is—

- 5 1. A frame, a segmental gear mounted thereon, a hook extending from said gear, a second gear meshing with said first-named gear, a link pivoted to said second gear, a lever pivoted to said frame and link, and means for operating said lever.
- 10 2. A frame, a hook, gearing adapted to move said hook from holding to releasing position, a link pivoted to the initial gear, and a lever pivoted to said frame and link, the pivot between said lever and link being adapted to stand in locking position when the hook is in holding position.
- 15 3. A frame, a pair of gears pivoted thereto and provided with extensions, a hook extending from one of said gears, said extensions abutting when the hook is in holding position, and means for operating said gears to move the hook from holding to releasing position.
- 20 4. A frame, a pair of gears pivoted thereto, a hook extending from one of said gears, said gears being provided with extensions which abut against each other when the hook is in holding position, a link pivoted to the extension of the initial member of said pair of
- 25 30 gears, and a lever pivoted to said link for

moving the hook from holding to releasing position.

5. A frame, a pair of gears pivoted thereto, a hook extending from one of said gears, said gears being provided with extensions which abut against each other when the hook is in holding position, a link pivoted to the extension of the initial member of said pair of gears, and a lever pivoted to the frame and link, said lever and link being connected by a pivot which is movable to stand in locking position when the hook is in holding position.

6. A frame consisting of a pair of parallel bars, a hook pivoted between said bars at the lower end thereof, a toggle and toggle-actuated means operating between the bars for swinging said hook, the actuating-arm of the toggle being pivoted to said frame forwardly of the pivot of the hook, and adapted to extend adjacent to and substantially parallel with the bars of the frame to lock the hook in its forward or holding position.

In testimony whereof I have hereunto set my hand, at Los Angeles, California, this 19th day of December, 1905.

HENRY ROBERTS.
